UNITED STATES PATENT OFFICE.

RONALD F. THOMSON, OF CHICAGO, ILLINOIS.

BOTTLE-FILLING DEVICE.

Application filed October 12, 1925. Serial No. 61,908.

My invention relates to new and useful improvements in a bottle filling device, and is more particularly directed to the filling tube and the valve thereof; and has for its 5 main object to provide such a bottle filling or liquid feeding device in which the valve is immediately and positively closed and a vacuum is created in the filling tube, so as to securely retain the remainder of the syrup or liquid in the tube as soon as the bottle is withdrawn from said tube; and another object is to provide means for adjusting the filling tube on the device so that the valve may be partly or entirely opened 10 for feeding the liquid, in order to suit the thickness or thinness of the liquid to be fed through the valve into the tube and to vary the time of closing said valve when the bottle is withdrawn.

20 Other objects will appear hereinafter.

The invention consists in the combinations and arrangements of parts hereinafter described and claimed.

The invention will be best understood by 25 reference to the accompanying drawings forming a part of this specification, and in which,

Fig. 1 is a vertical sectional view of my invention, showing the mechanism in its 30 lowered position and the valve closed,

Fig. 2 is a similar vertical sectional view, showing the mechanism in the elevated position and the valve open, and

Fig. 3 is a plan view of the invention.

35 In the drawings, I have shown the preferred form of construction embodying my invention and this form comprises a bracket 6 mounted fluid tight in the bottom of a liquid containing tank 7, as by means of screws 8 or the like. A tube 9 is slidably mounted through the lower part 10 of the bracket and through a packing gland 11 in the upper part 12 of the bracket. The sleeve 13 provided with a flanged packing 40 nut 14 at its lower end is mounted on said tube and threaded into the upper part 12 of the bracket. Soft material 15, like cotton, is placed around the tube between said packing nut 14 and gland 11. The tube 9 is 45 provided with valve openings 16 adjacent its upper end, said openings being closed fluid tight in sleeve 13 when the tube is lowered, as shown in Fig. 1, and open or exposed above said sleeve 13 when the tube 50 is in its elevated position, as shown in Fig.

2. A filling cup 17 is mounted with packing 18, preferably a rubber bushing, on sleeve 13, and said cup is provided with a bridge or yoke 19 on its upper end through which extends a threaded stem 20 arising 60 from the closed upper end 21 of tube 9. Lock nuts 22 are provided on said stem, above and below bridge 19, for adjusting and holding the tube in the desired position within sleeve 13, whereby the valve 65 openings 16 may be exposed partly or entirely above the top of sleeve 13, as desired. A spring 23 is mounted on tube 9 and seated between collars 24 engaging the gland 11 and the lower part 10 of the bracket. A 70 centering bell 25 is mounted on the flanged lower part 26 of the tube for centering the top of the bottle beneath the lower open end of said tube.

With this form of construction the valve 75 openings 16 may be adjusted to be exposed to any desired extent above sleeve 13, to suit the consistency of the fluid and also the time desired in which the spring 23 will automatically close said valve when the bottle is withdrawn from bell 25, and in view 80 of the fact that the top 21 of the tube is closed, the valve openings 16 are sealed in the sleeve against the admission of atmospheric pressure whereby the liquid in dropping will cause a reduction of pressure of 85 the air entrapped in the tube so that when the combined weight of air pressure and liquid within the tube becomes less than the atmospheric pressure at the lower end of 90 the tube, the remainder of the liquid in the lower part of the tube will be retained and waste thereby avoided when the bottle is withdrawn from the bell. When it is desired to vary the amount of fluid taken in 95 the cup 19, from the fluid in tank 7, a solid article is preferably placed in the cup, or the size of the cup is constructed to suit the particular size of bottle to be filled with this device.

100 While I have illustrated and described the preferred form of construction for carrying my invention into effect, this is capable of variation and modification without departing from the spirit of the invention. 105 I, therefore, do not wish to be limited to the precise details of construction set forth, but desire to avail myself of such variations and modifications as come within the scope of the appended claims.

Having described my invention, what I claim as new and desire to secure by Letters Patent is:

1. A device of the class described comprising a container with a tube slidably mounted therein, a sleeve in said container and surrounding said tube, and a cup attached to said tube and slidable therewith on said sleeve, there being valve openings on said tube which are exposed when the tube is moved in one direction and are closed when the tube is moved in the opposite direction, so that the liquid in dropping will cause a reduction of the air entrapped in the tube and result in the retention of the fluid remaining in the lower part of said tube.
2. A device of the class described comprising a container, a tube slidably mounted therein, a cup mounted on said tube, there being valve openings in said tube to be moved into open or closed position, means coacting with said openings for controlling the flow therethrough, and means for adjustably connecting said cup and tube to vary the exposable part of said valve openings.
3. A device of the class described comprising a fluid tank with a bracket, a tube movably mounted in said bracket, a cup on said tube and movable therewith, and a sleeve surrounding said tube and being stationary with said bracket, there being valve

openings in said tube near the upper end thereof adapted to be opened above said sleeve when the tube and cup are elevated and to be closed when they are lowered.

4. A device of the class described comprising a fluid tank, a bracket on said tank, a tube with a closed top slidably mounted in said bracket, a cup mounted on said tube to slide therewith, a sleeve in which the tube has sliding fit and around which the bottom of the cup has sliding fit, extending upward into the tank and mounted on the bracket, there being valve openings in said tube adapted to open communication with the cup above the sleeve when the tube and cup are elevated and to be closed by the sleeve when the tube and cup are lowered.

5. A device of the class described comprising a fluid tank with a bracket, a tube movably mounted therein and having a closed upper end, a sleeve on said bracket and surrounding said tube, a cup on said sleeve, a bridge on said cup and a stem with lock nuts on said tube for adjustably connecting said cup and tube, there being valve openings in said tube which are exposed above said sleeve when the tube is elevated, and a spring for lowering said tube thereby automatically closing said valve openings.

In testimony whereof I have signed my name to this specification.

RONALD F. THOMSON.
